UNITED STATES PATENT OFFICE.

WARREN F. CLARK, OF WARREN, PENNSYLVANIA, ASSIGNOR TO AUTOMATIC ELECTRIC HEATER COMPANY, OF WARREN, PENNSYLVANIA, A CORPORATION OF DELAWARE.

LIQUID-HEATING UNIT.

Application filed April 2, 1921. Serial No. 458,062.

To all whom it may concern:

Be it known that I, WARREN F. CLARK, a citizen of the United States, residing at Warren, in the county of Warren and State of Pennsylvania, have invented a certain new and useful Improvement in Liquid-Heating Units, of which the following is a full, clear, and exact description.

This invention relates to a water or other liquid heating device and is particularly directed to a construction which embodies an electrical heating element by which the liquid is heated.

Additionally the invention contemplates the association of the electrical heating element with a tubular member through which the liquid to be heated is circulated, and additionally contemplates the provision of a sleeve of insulating material of the particular construction which serves to support and carry the electric resistance wire.

Reference should be had to the accompanying drawings forming a part of this specification in which Fig. 1 represents a vertical section of a heating element associated with a container which is in part shown; Fig. 2 is an elevation of a portion of the support and carrier of the electric resistance wire; Fig. 3 is a section upon the line 3—3 of Fig. 1; Fig. 4 is a sectional plan of the construction shown in Fig. 2.

Referring to the drawing, 1 indicates the bottom of a liquid container and the side wall represented at 2. It will be understood that the container is only partially represented, as various and differing forms of containers may be used with the heating unit.

The heating unit itself comprises a member 3 which is hollow, being closed at one end, but open at the other. This member at its upper end is provided with an annular shoulder 3^a. Upon the outer portion of the member 3 there is or may be a flange 4 and above the same a threaded portion 5 by which the member 3 may be mounted in the threaded opening of any suitable container.

Cooperating with the shoulder 3^a and extending upwardly therefrom is a cylindrical member 6 which is preferably of metal which is a good conductor of heat, such for instance as copper. Surrounding the cylindrical member 6 is a tubular member which is generally represented at 7. This tubular

member is made of insulating material and 55 may conveniently be made of porcelain or some material which is analogous thereto. Upon the outer surface of the member 7 there are formed spiral ribs so that the spaces between the ribs form convenient 60 passages in which electrical resistance wires or ribbons may be located. In the present instance there are two independent spirals which progress in the same direction. One 65 of these spirals may start at a point indicated at 7^a, while the other of the spirals may conveniently originate on the opposite portion of the member 7 as that shown in Fig. 2 as indicated at 7^b. In one of these spirals, for instance the spiral 7^a, may be 70 laid a conductor A, while in the other of the spirals may be laid a conductor B.

From the foregoing it will be seen that the number of spirals may be multiplied to provide the desired number of spirals for 75 any given number of electric resistance elements and when each resistance element is laid in its spiral it is effectually insulated from the resistance element which lies in adjacent spirals. This construction is very 80 beneficial inasmuch as it facilitates the winding of the resistance element and effectually provides against short circuits between adjacent convolutions of the resistance element.

The space between the cylindrical member 6 and the member 7, which space is represented at 8, may be filled with any suitable material which will conduct the heat from the member 7 to the tubular member 8, as 90 for instance talc.

Surrounding the member 7 is a cylindrical casing 9 which at its lower end is secured to the member 3, preferably by providing the member 3 with a shoulder as indicated at 95 10 in Fig. 1. The space between the member 7 and the member 9, which is indicated at 11 in Fig. 1 may be packed with any suitable heat insulating material.

At the outer end of the structure which 100 has just been described, there is an annular member 12, which is secured to the outer end of the cylindrical member 6 and the cylindrical member 9, forming a closure and holding the member 7 against displacement. 105

Extending longitudinally through opposite portions of the wall of member 3 are drilled openings which are indicated at 13

and 14 and in each of these openings there is a tube of insulating material such as indicated at 15 and at 16. These tubes are for the purpose of receiving conductors which 5 are connected with the ends of the resistance material which are laid in the spiral grooves of the member 7.

As a convenient means for providing terminals for the conductors before described, the member 3 may be provided with an extending member 15^a provided with two or more openings which receive retaining members such as a screw 16^a with a nut 17 thereon. The screw and nut are of course 15 suitably insulated from the portion 15^a.

The wall of the member 3 at a portion above the threaded part 5 is provided with one or more openings such as indicated at 18. These permit the entrance of liquid 20 which may circulate upwardly through the tubular member 6.

The operation of the device will be obvious, that is to say, liquid may enter through the openings 18 and circulate upwardly through the tube 6, taking up heat from this tube as the liquid passes upward. The colder liquid within the container and upon the outside of the heating element which has just been described, will of course 30 sink toward the lower portion, and by convection currents cause to circulate through the tube 6.

Due to the fact that the heating element is so advantageously placed with respect to 35 the tube 6, and further that the diameter of the tubular member 6 may be made comparatively small with respect to the length, the liquid which circulates through the tube 6 will rapidly absorb heat.

Having described my invention, I claim 40
1. In a device of the character described, the combination with a tubular member which is open at the bottom and the top to permit circulation of water, of a second tubular member surrounding the first tubular member, said second tubular member being 45 provided with a plurality of independent spiral grooves which proceed in the same direction with respect to the axis of the tubular member and are of the same pitch, and electrical resistance elements laid in said 50 grooves.

2. In a device of the character described, the combination with a metal tubular member which is open at the bottom and the 55 top to permit circulation of water, a second tubular member surrounding the first tubular member and in spaced relation thereto, packing material which is a good heat conductor occupying the space between the said tubular members, the second tubular member being provided with a plurality of independent spiral grooves extending longitudinally thereof, the said grooves being of 60 the same pitch, a casing surrounding the 65

second tubular member and packing material between the second tubular member and the casing.

3. In a device of the character described, a base portion having a hollow interior and one or more openings through the wall thereof whereby circulation of a liquid through the interior of the tubular member is obtained, a tubular member mounted upon a base portion and forming an extension of the hollow interior of the base portion, a second tubular member surrounding the first tubular member and mounted upon the base portion, said second tubular member being provided with a plurality of independent spiral grooves upon the outer surface thereof, said grooves extending longitudinally of the tubular member and being of the same pitch, and electric resistance elements occupying the said grooves. 70 75 80 85 90 95 100

4. In a device of the character described, a base member having a hollow interior and having an opening through the wall thereof, said member having a shoulder adjacent one end, a tubular member cooperating with said shoulder and forming an extension of the hollow interior of the base member, a second tubular member of insulating material, which tubular member surrounds the first mentioned tubular member and is mounted upon the shoulder of the base member, said second tubular member being provided with a plurality of spiral grooves on the outer surface thereof, which grooves extend longitudinally of the second tubular member and are of the same pitch, electrical resistance elements occupying the said grooves, a casing surrounding the second tubular member and mounted at one end thereof upon the said base member. 105 110 115 120 125 130

5. In a device of the character described, a base member having a hollow interior and open at one end, a tubular member mounted upon the base member and forming an extension of the interior of the base member, 110 a second tubular member of insulating material which surrounds the first tubular member and is mounted upon the base member, said second tubular member being provided with a plurality of spiral grooves 115 upon the outer surface which grooves extend longitudinally of the tubular member and the grooves being of the same pitch, and resistance elements occupying the said grooves. 120

6. In a device of the character described, a base member having a hollow interior and open at one end, a tubular member mounted upon the base member and forming an extension of the interior of the base member, 125 a second tubular member of insulating material which surrounds the first tubular member and is mounted upon the base member, said second tubular member being provided with a plurality of spiral grooves 130

- upon the outer surface which grooves extend longitudinally of the tubular member and the grooves being of the same pitch, and resistance elements occupying the said 5 grooves, the said base member being provided with a longitudinally extended opening through which a conductor may extend for cooperation with the electrical resistance element.
- 10 7. In a device of the character described, a base member having a hollow interior and having an opening through the wall thereof, said member having a shoulder adjacent one end, a tubular member cooperating with 15 said shoulder and forming an extension of the hollow interior of the base member and adapted to have a liquid circulate therethrough, a second tubular member of insulating material, which tubular member 20 surrounds the first mentioned tubular member and is mounted upon the shoulder of the base member, said second tubular member being provided with a plurality of spiral grooves on the outer surface thereof, which 25 grooves extend longitudinally of the second tubular member and are of the same pitch, electrical resistance elements occupying the said grooves, a casing surrounding the sec-
- ond tubular member and mounted at one end thereof upon the said base member, the 30 said base member being provided with a longitudinally extended opening through which a conductor may extend for cooperation with the electrical resistance element.
8. In a device of the character described, the combination with a base member having a hollow interior and open at one end, a tubular member mounted upon the said base member and forming the extension of the 35 interior of the base member, a second tubular member surrounding the first tubular member and supported by the said base member, said second tubular member being provided with a plurality of grooves, an 40 electric resistance element occupying the said grooves, the said base member being provided with a longitudinally extended opening in a wall thereof and adapted to receive a connector for cooperation with the resistance element, said base member being provided with an extension, and insulated conductor retaining members carried by said extension.

In testimony whereof, I hereunto affix my signature.

WARREN F. CLARK.
